DESIGN FOR AN AUTOMOBILE BODY

Joseph Ledwinka, Philadelphia, Pa., assignor to
Edward G. Budd Manufacturing Company,
Philadelphia, Pa., a corporation of Pennsyl-
vania

Application June 24, 1933, Serial No. 48,523

Term of patent 14 years

To all whom it may concern:

Be it known that I, JOSEPH LEDWINKA, a citizen
of the United States, residing at Philadelphia,
in the county of Philadelphia and State of Penn-
sylvania, have invented a new, original, and orn-
amental Design for an Automobile Body, of
which the following is a specification, reference
being had to the accompanying drawing which
forms a part hereof.

The figure is a three-quarter front perspective
view of the new design for automobile body.

The dominant features of this invention have
been illustrated in full lines.

I claim:

The ornamental design for an automobile body,
as shown and described.

Signed at Philadelphia, county of Philadelphia,
State of Pennsylvania, this 21 day of June, 1933.

JOSEPH LEDWINKA.
